Patented Apr. 2, 1918.

UNITED STATES PATENT OFFICE.

BENJAMIN LEONARD GETMAN, OF SPRINGFIELD, MASSACHUSETTS, ASSIGNOR TO HARLEY COMPANY, OF SPRINGFIELD, MASSACHUSETTS, A CORPORATION OF MASSACHUSETTS.

VALVE.

1,261,509.

Specification of Letters Patent.

Patented Apr. 2, 1918.

Application filed December 5, 1917. Serial No. 205,652.

To all whom it may concern:

Be it known that I, BENJAMIN L. GETMAN, a subject of the Emperor of Germany, but having declared my intention of becoming a citizen of the United States of America, residing at Springfield, in the county of Hampden and Commonwealth of Massachusetts, have invented certain new and useful Improvements in Valves, of which the following is a specification.

This invention relates to improvements in valves or shut off devices for crucibles. It is particularly designed for stopping the flow of molten material of low specific gravity, particularly aluminum, or any of its alloys. In the making of castings of aluminum, by what is known as "die casting", the metal is forced into the dies under considerable pressure, in fact, about 200 pounds per square inch. It has been found difficult to effectually shut off the flow of the metal from the crucible to the mold after the mold or die has been filled, resulting oftentimes in serious injury to the workman and loss of material by spilling on the floor of the foundry, requiring its being remelted and purified. Broadly, the invention comprises a shut off valve which is preferably conical in form, that is inserted in the mouth or opening of the crucible, which is located over the mold. Encircling the seat portion of the valve is a rib, preferably semi circular in cross section to provide a small contact or area with the opening of the crucible, whereby the flow of molten metal will be effectually shut off. A further object of the invention is to provide a valve which will permit the escape of the confined air in the die or mold so that, as the molten material flows into the die the air therein can readily escape. Broadly, this part of the valve is formed with an opening that is arranged in the axis thereof, the lower end of the opening having a plug formed of laminations of rolled steel, the space between the laminations permitting the air to readily escape from the mold, but preventing the molten metal from flowing therethrough.

Referring to the drawings:

Figure 1 is a sectional view through the

axis of the crucible showing the conical shaped plug or valve with the rib thereon, also the plug of laminations located therein.

Fig. 2 is a transverse sectional view on the line 2—2 of Fig. 1 showing the air ducts 55 in the body portion of the plug.

Fig. 3 is a horizontal sectional view on the line 3—3 of Fig. 1 showing the threaded connection between the inner and outer portions of the plug and also illustrating the 60 air ducts.

Fig. 4 is a horizontal sectional view of the line 4—4 of Fig. 1 showing the arrangement of the inner and outer portions of the plug in relation to the mouth of the 65 crucible.

Referring to the drawings in detail: 1 designates the crucible for containing the molten material, which is formed with the usual outlet or opening 2, preferably conical in form as shown. The mold or die which is to form the casting is conventionally indicated at 3. The sprue or opening in the mold through which the molten material flows, is indicated at 4. The plug as a 75 whole, for closing the opening 2 of the crucible, is indicated at 5 and is formed with a conical surface 6, which is substantially parallel with the conical surface 7 of the mouth of the crucible. The plug 5 is 80 formed with a rib 8, which is located substantially one half of the distance between the upper and lower ends of the inclined portion of the plug whereby an annular space between the plug and the mouth of the 85 crucible is provided, as shown. This rib, it will be noticed, is made semi circular in form so that only a small area of contact engages the surface 7 of the opening in the crucible. This rib is made semi circular for 90 the purpose of spacing the plug from the opening in the crucible as indicated above at 2, and, on account of the narrow passageway between the plug and the inner wall of the mouth of the crucible, only a small quantity of molten material will flow down into the annular passageway above the rib 8, thus preventing the mouth of the crucible 95 becoming extremely hot. Or, in other words, keeping this part of the crucible

100

comparatively cool and also the ribs 8. It is to be understood that the crucible is filled with molten material of low specific gravity, as aluminum, which is largely used in die casting. When the plug 5 is raised, the molten material flows into the mold 3 under the pressure that is normally exerted on the closed crucible. The confined air in the mold must be allowed to escape as quickly as possible and in order to provide a ready means to allow of this escape, the plug 5 is formed with an axial opening 9 the lower part of which is made conical. In this opening is located a stem 10 formed with grooves 11 and with passageways 11', which open into grooves 11. The conical opening 12 in the plug 5 is filled with a similar shaped plug, preferably composed of laminations of rolled steel indicated at 13, which are held together by means of rivets 14. I have found in practice that the lower end of the laminations 13, at the sprue or opening 4 of the mold may possibly be slightly coated with a thin film of molten metal after the die or mold is filled, but the next time that a die, or mold, is filled the incoming molten metal will cause it to be instantly removed and the air confined in the die, or mold, will escape. The air passages between the laminae of the plug are very small, not over one or two thousandths of an inch, and effectually prevents any of the molten metal gaining access to the spaces between the laminations. The purpose of using laminations is to allow the confined air in the mold 3 to readily escape through the passageways 11' and 11, but will, at the same time, prevent the molten material from flowing upward through the opening 12 in which the laminated plug is placed. The passageways 11 lead into smaller passageways 15 at the upper end of the plug 5 and from there to the atmosphere. The threaded end 16 provides a connection for a suitable extension piece that will extend a considerable distance above the crucible 1 whereby the plug 5 may be operated. On account of the small annular passageway 2 between the plug 5 and the mouth of the crucible, the molten material will flow down through the opening of the crucible in a comparatively small stream and in this way the volume of the flow will be easily regulated. Should the rib 8 fail to make a perfect joint, to effectually seal the flow of the material after the plug 5 is forced downward, this plug may be rotated about its axis to grind the semi circular rib 8 to its seat. Should any particles of foreign substance find lodgment between the rib 8 and the mouth of the crucible, these will be readily removed permitting a perfect joint to be formed, which would not otherwise be the case if the rib 8 was omitted.

From this construction it will be seen that I have provided a plug for closing the outlet opening of a crucible and one that will effectually prevent leakage when molten material of low specific gravity is to be shut off; also one that will permit the escape of the confined air in the molds as the material is forced into the mold.

What I claim is:

1. A valve for a crucible for shutting off the flow of molten material comprising a conical shaped member having a smooth surface which is formed with a single rib at substantially mid-way of the vertical length of the conical shaped portion of said member, said rib being semi circular in cross section, said rib being designed to engage a conical shaped opening in the outlet of the crucible for spacing the body part of the plug from the surface of the opening, whereby the curved surface of the valve will form a tight joint between the plug and the opening of the crucible.

2. In a device of the kind described, the combination, with the outlet opening of a crucible having a conical shaped mouth, a plug for the opening and of similar conformation, but of less diameter than the outlet of the opening of the crucible, a rib on the plug for spacing the plug from the wall of the mouth of the opening, means to permit the air confined in the mold to escape through the plug as the metal is introduced into the mold.

3. In a device of the kind described, the combination, with the crucible, formed with a conical shaped outlet, a plug of similar conformation, but of less diameter, a rib semi circular in cross section for spacing the plug from the wall of the outlet opening, means to permit the air confined in the mold to escape through the plug as the metal is introduced into the mold under pressure, said means comprising a conical shaped plug formed of laminations to permit the air to flow upward therethrough and at the same time to prevent the flow of molten material.

4. A plug for closing the opening of a crucible, comprising a conical shaped member formed with an opening therethrough; a plug within the opening and having a stem formed with grooves to provide air passages, said plug being formed with laminations and fitted into the opening of the plug.

5. In a device of the kind described, a plug having a conical shaped end, a rib disposed at substantially midway of the length of the plug and integral therewith for engaging a conical shaped outlet opening of a crucible, whereby the body of the plug is spaced from the inner wall surface of the opening both above and below the rib to provide a narrow annular passage, said rib being semi-circular in cross section to provide

a comparatively narrow seat area between the plug and the mouth of the crucible.

6. In a plug for closing the mouth of a crucible which contains molten material of low specific gravity, as aluminum, an opening in the plug, the lower part of the opening being made conical, means for closing

the opening comprising a plurality of laminations formed of thin sheet steel suitably secured together to permit the confined air 10 within a mold to escape and prevent the flow of molten material, means to permit the confined air to escape from the plug.

BENJAMIN LEONARD GETMAN.
